7-2-3-

FIG. 1 is a perspective view of a shaver showing our new design, it being understood that the cutting teeth are continuous across the shaving head and partially omitted in FIGS. 1, 3 and 4 for ease of illustration;

FIG. 2 is a right side elevational view;

FIG. 3 is a top plan view;

FIG. 4 is a front elevational view;

FIG. 5 is a rear elevational view; and

FIG. 6 is a bottom plan view.

We claim:

The ornamental design for a shaver, as shown and described.
